UNITED STATES PATENT OFFICE.

FREDERICK RATCLIFF, OF NEW BEDFORD, MASSACHUSETTS, ASSIGNOR TO
THE PAIRPOINT MANUFACTURING COMPANY, OF SAME PLACE.

DESIGN FOR A DISH.

SPECIFICATION forming part of Design No. 22,172, dated January 31, 1893.

Application filed February 23, 1892. Serial No. 422,585. Term of patent 7 years.

To all whom it may concern:

Be it known that I, FREDERICK RATCLIFF, of New Bedford, in the county of Bristol and State of Massachusetts, have invented and produced a new and original Design for a Vessel, of which the following is a specification, reference being had to the accompanying drawings, forming part hereof.

Figure 1 is a plan; and Fig. 2 an end view of a dish showing my design, these two views being deemed necessary to fully illustrate my design.

The design consists in a dish or vessel having re-entrant corners with the rim fluted be-

tween the corners, so that the top edge of the dish shows full sweeping curves at the corners, and smaller curves formed by flutings.

A is the dish with the full sweeping curves b from a to a' and the smaller curves b' from a to a' formed by fluting the rim.

What I claim is:

The design for a dish herein shown and described.

FREDERICK RATCLIFF.
